Attorney

UNITED STATES PATENT OFFICE.

PAUL NEIDHARDT, OF CHICAGO, ILLINOIS.

BUTTON.

SPECIFICATION forming part of Letters Patent No. 527,502, dated October 16, 1894.

Application filed February 9, 1893. Serial No. 461,653. (No model.)

To all whom it may concern:

Be it known that I, PAUL NEIDHARDT, of Chicago, in the State of Illinois, have invented certain new and useful Improvements 5 in Buttons; and I do hereby declare the following to be a full, clear, and exact description of the invention, such as will enable others skilled in the art to which it appertains to make and use the same.

10 My invention relates to an improvement in buttons and more particularly to that class known as collar and cuff buttons, the object being to construct a button in two parts which will when in its normal or operative 15 position clamp the goods to which it is attached and prevent turning or a separation of the parts comprising the button.

With this end in view my invention consists in certain novel features of construction 20 and combinations of parts as will be herein-after more fully described and pointed out in the claim.

25 In the accompanying drawings, Figure 1 is a perspective view of the completed button. Fig. 2 is a sectional view showing the button attached to the collar band of a shirt, and Fig. 3 is a detached perspective view.

30 A represents the completed button, which is constructed in two parts as shown in Fig. 3. The upper part of said button is provided with the ordinary head B, from which projects the shank C. This shank is preferably made conical or bell-shaped, the free or enlarged end of which is slightly flattened as 35 at a, for the purpose to be hereinafter explained. The shank C is conically bored as shown at d, said bore having its greatest diameter at the bearing surface a, while its smallest diameter is at a point where the 40 screw threaded hole e begins, which latter extends the desired distance up in the shank C toward the head B.

45 The lower part of the button A, is composed of a base or bottom F and a screw threaded post G, which latter is integral with the bottom F. The outer surface or circumference of the bottom F is bent over on itself as at b and forms a bearing surface for the shirt band when the button is in the position 50 shown in Fig. 2. The portion of the button

F at the base of the screw is also conical in form as shown at c, which latter tends to force the shirt band or that part surrounding the button hole into the conically bored shank C, when the latter is screwed on the 55 threaded post G.

The button is secured to a shirt band in the following manner:—The button is first separated as shown in Fig. 3. The screw threaded post G of the lower portion of the button is 60 passed through the button hole of the shirt band from the rear and is held therein until the front portion of the button is screwed on the post G, which is accomplished by placing the conically bored or bell-shaped end of shank 65 C over the post G and pressing the former backward until the latter comes in contact with the screw threaded hole e, after which the parts are locked together by giving the shank C a few turns to the right. By thus 70 securing the button to the shirt, it will be seen that the entire shank is for the sole use of accommodating the ends of the collar.

Having fully described my invention, what I claim as new, and desire to secure by Letters 75 Patent, is—

As an article of manufacture, a button made in two separable parts constructed the one to screw into the other and receive the object to which the button is attached between them, one part having a head or enlargement and a funnel shaped shank, screw threaded internally, the smaller end of the shank being next to the head or enlargement, and the other part consisting of an externally 80 screw threaded post and an enlargement, the base of the post being conical or funnel shaped to enter the open end of the shank, and the inner face of the enlargement having a recessed seat corresponding in shape and size 85 to the free edge of the shank, substantially to the free edge of the shank, substantially 90 as and for the purpose described.

In testimony whereof I have signed this specification in the presence of two subscribing witnesses.

PAUL NEIDHARDT.
